P. R. FORMAN.
FARE RECORDING APPARATUS.
APPLICATION FILED JULY 22, 1919.

1,422,686.

Patented July 11, 1922.

UNITED STATES PATENT OFFICE.

PARIS R. FORMAN, OF RAHWAY, NEW JERSEY, ASSIGNEE TO NATIONAL PNEUMATIC COMPANY, OF NEW YORK, N. Y., A CORPORATION OF WEST VIRGINIA.

FARE-RECORDING APPARATUS.

1,422,686.

Specification of Letters Patent. Patented July 11, 1922.

Application filed July 22, 1919. Serial No. 312,5.

To all whom it may concern:

Be it known that I, PARIS R. FORMAN, a citizen of the United States, residing at Rahway, county of Union, State of New Jersey, have made a certain new and useful Invention in Fare-Recording Apparatus, of which the following is a specification.

This invention relates to fare collection apparatus, and particularly to such apparatus in which registration is effected, and an indicating device, employed in connection with each fare paid.

The object of the invention is to provide an apparatus of the nature referred to which is simple and efficient to insure a distinct registration of fare for each passenger and a distinct operation of the indicating device regardless of the amount of payment made.

A further object of the invention is to provide an apparatus of the character referred to which prevents inaccuracies of registration or signal indications due to rapidity of deposit of the coins or fares paid.

A further object of the invention is to provide a delayed movement of the recording and signal operating devices to insure separate, distinct and corresponding indications or signals and registrations under conditions of rapid deposit of coins.

Other objects of the invention will appear more fully hereinafter.

The invention consists substantially in the construction, combination, location, and relative arrangement of parts, all as will be more fully hereinafter set forth, as shown in the accompanying drawing, and finally pointed out in the appended claims.

Referring to the accompanying drawing:

Fig. 1 is a view in front elevation, somewhat diagrammatic, showing a registering and indicating apparatus embodying the principles of my invention.

Fig. 2 is a similar view in side elevation of the same.

Fig. 3 is a detail view in section on the line 3, 3, Fig. 2.

Fig. 4 is a view in section on the line 4, 4, Fig. 3, looking in the direction of the arrows.

Referring to the drawing: 5 designates a fare registering odometer operated in any suitable or desirable manner, and by means which form no part of my present invention through the operation of a shaft 6. Upon 55 this shaft is mounted a pinion 7 which

meshes with and drives a pinion 8 upon a stud shaft 9, one portion 10 of which is threaded. Upon the unthreaded portion of rod 10 is mounted a block 11 which is connected to stud shaft 9 to rotate therewith. Upon the threaded portion 10 of the stud shaft is threaded a cooperating block 12. A coil spring 13 has one end connected as at 14 to the block 12, and at the other end as at 15 to block 11. Upon their opposed faces the blocks 11, 12 are respectively provided with fingers or projections 16, 17, which engage each other. The spring 13 normally holds these projections against each other, but the drum 12 is permitted to revolve 70 backwardly against the tension spring 13 if necessity therefor arises, and when so revolved reversely by reason of its threaded engagement with the threaded portion 10 of stud 9 it backs away from the block 11 to 75 cause the lug 17 to be carried out of contacting relation with respect to lug 16. As soon however as the retarding influence exerted on block 12 is released the tension of spring 13 is applied to rotate said block in a direction to again cause it to approach and to catch up with the block 11. The block 12 carries an arm or finger 18 adapted to be brought into electrical contact respectively with levers 19, 20, which levers are pivotally 80 mounted as at 21, 22, respectively, and are connected together and to the cores 23, 24, of solenoids 25, 26, by means of a rod 27. A solenoid or magnet coil 28 operates an armature lever 29 through which a signal device, such, for instance, as a bell 30, is operated. The armature lever through a pawl and ratchet connection 31 operates an odometer or register device 32. Current from a battery or other suitable source is supplied 95 through wire a, from which the circuit divides, one part including wire b, the coils of magnet 28, wire c, the coils of magnet 26, wire d, lever 20, from whence circuit is completed when finger 18 contacts with lever 20 100 through the block 12, rod 10, and wire e, to ground. The other branch of the supply circuit extends from supply wire a, through wire f, the coil of magnet 25, wire g, lever 19, and thence on to ground through finger 105 18, block 12, shaft 10, and wire e, whenever the finger 18 is brought into contact with the lever 19.

The operation of the apparatus is exceedingly simple. When the operating shaft 110

6 of register device 5 is rotated, rotations are imparted through gears 7, 8, to drum or block 11 and shaft 9, and under normal conditions through the spring 13 to block 12, 5 the said blocks 11, 12, and shaft 9 revolving as a unit. When the finger is brought, for example, into contact with contact lever 20, the circuit of magnet 28 and of magnet 26 is thereby completed. This causes an actuation 10 of the signal device 30 and a registration and operation of the odometer 32. It also causes lever 20 to be withdrawn from the path of finger 18 and the lever 19 to be drawn into the path of finger 18. When the 15 finger 18 in its rotative movements is brought into contact with lever 19 circuit is completed from the current source through wire 4, wire 6, magnet 25, lever 19, finger 18, block 12, shaft 10, wire 6 to ground. This 20 withdraws the lever 19 from the path of finger 18 and restores lever 20 to the path of said finger.

It will be observed that flexibility is thus permitted in the arrangement of the blocks 25 11, 12, permitting relative movements thereof, that is, should registrations on the register 5 be accomplished too rapidly the danger is incurred of preventing corresponding accurate registrations to be made on registering 30 device 32 and indicator device 30. However with the flexibility permitted in the relative movements of drums or blocks 11, 12, the action of the registering device 32 and indicator 35 30 may be delayed sufficiently to accomplish a complete actuation thereof and then the instant return of the block 12 to normal position with reference to block 11 irrespective of the total registrations made in the register device 5.

40 An apparatus above described although suitable for use where fixed and definite amounts such as five cent fare registrations are made, is especially suitable where the fares may be more than five cents, namely, 45 six cents, or seven cents, and so on. In practice the ratio of gears 7, 8, should be made such that shaft 9 makes one complete revolution for each fare recorded on the counter 5, consequently, the ratio of these 50 gears may be changed according as the standard fare is five cents, six cents, seven cents, or the like. In other words, the apparatus is adapted for any desired fare by suitably regulating or changing the ratio of 55 the pinion 7, 8. The desirable thing in this regard being that whatever the fare amounts registered on the counter device 5, whether it be five cents, six cents, seven cents, etc., for each registration, the shaft 9 is to be rotated through one revolution for each registration on the counter device 5.

Having now set forth the objects and nature of my invention, and a construction embodying the principles thereof, what I claim 60 as new and useful, and of my own inven-

tion, and desire to secure by Letters Patent is—

1. In a fare registering apparatus, the combination with a registering mechanism, and a signal device, of means controlled by 70 the former for actuating the latter, said means including devices to secure a delayed operation of the signal device with respect to the operation of the registering mechanism. 75

2. In a fare registering apparatus, the combination with a registering mechanism, including an operating shaft therefor, an indicator, and means to actuate the same, of devices operated from said shaft for controlling said indicator actuating means, said devices including a flexible connection to secure a delayed operation of the signal device with respect to the operation of said shaft. 80 85

3. In a fare registering apparatus, the combination with a registering mechanism, a signal device, and electrically operated means to actuate the same, of means operated by the registering mechanism for controlling the circuits of the electrically operated signal actuating means, and including devices to secure a delayed operation of the signal device with respect to the operation of the registering mechanism. 90 95

4. In a fare registering apparatus, the combination with a registering mechanism, a signal device, and electrically operated means to actuate the same, and contact devices to control the circuit of said signal actuating means, of relatively separable yieldingly connected devices operated by the registering mechanism for controlling said contacts. 100

5. In a fare registering apparatus, the combination with a registering mechanism, a signal device, and electrically operated means to actuate the same, and contact devices to control the circuit of said signal actuating means, of automatically acting mechanism including a cooperating contact device, a member connected to operate coincidently with the registering mechanism, and yielding connections between said member and cooperating contact. 110 115

6. In a fare registering apparatus, and in combination with a register device and a signal device, of a shaft driven from the register device, a member carried by said shaft to rotate therewith but movable along the same when restrained from rotation therewith, means for yieldingly restraining said member from rotation with said shaft, and means controlled by the rotation of said member for actuating said signal device. 120 125

7. In a fare registering apparatus, and in combination with a register device and a signal device, of a shaft driven from the register device, cooperating members mounted on said shaft, one of said members con- 130

- 5 nected to rotate with said shaft, said members having engaging projections, means yieldingly connecting said members to maintain said projections in engagement to normally cause both members to revolve with said shaft, one of said members mounted for movement away from the other to cause disengagement of said projections, and means controlled by said last named member for actuating the signal device.
- 10 8. In a fare registering apparatus, and in combination with a register device and a signal device, of a shaft driven from the register device, a block mounted on said shaft to revolve therewith, a cooperating block threaded upon said shaft, a spring connecting said blocks, and means controlled by said cooperating block to actuate said signal device.
- 15 9. In a fare registering apparatus, and in combination with a register device and a signal device, of a shaft driven from the register device, a block mounted on said shaft to revolve therewith, a cooperating block threaded upon said shaft, engaging projections on said blocks, a spring to yieldingly maintain said projections in engagement with each other, and means controlled by said cooperating block to actuate said signal device.
- 20 10. In a fare registering apparatus, and in combination with a register device and a signal device, of a shaft driven from the register device, a block mounted on said shaft to revolve therewith, a cooperating block threaded upon said shaft, engaging projections on said blocks, a spring to yieldingly maintain said projections in engagement with each other, and means controlled by said cooperating block to actuate said signal device.
- 25 11. In a fare registering apparatus, and in combination with a register device and a signal device, of a shaft driven from the register device, a block mounted on said shaft to revolve therewith, a cooperating block threaded upon said shaft, engaging projections on said blocks, a spring to yieldingly maintain said projections in engagement with each other, a finger carried by said cooperating block, and means to be engaged by said finger for controlling the operation of said signal device.
- 30 12. In a fare registering apparatus, and in combination with a register device, and a signal device, of means driven from and in definite ratio to the speed of said register device for controlling the operation of said signal device with respect to the operation of the register device, said means including separable retarding connections to permit delayed action of the signal device.
- 35 13. In a fare registering apparatus, and in combination with a register device and a signal device, of means driven from and in definite ratio to the speed of said register device for controlling the operation of said signal device, said means including a yielding separable member to permit delayed operation of the signal device with respect to the operation of the register device.
- 40 14. In a fare registering apparatus, and in combination with a register device and a signal device, contact arms connected to move together, magnets for moving said arms in alternate directions, an electrical device to operate the signal device, the circuit of said electrical device also including one of said magnets and one of said arms, the other of said arms included in the circuit of the other of said magnets, and means driven from and in definite ratio to the speed of said register device for controlling the circuits through said arms.
- 45 In testimony whereof I have hereunto set my hand on this 12th day of July, A. D. 1919.

PARIS R. FORMAN.
